(57) **CLAIM**

The ornamental design for a health pot, as shown and described.

DESCRIPTION

FIG. 1 is a front view of the health pot, showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof, shown in an alternative state of use; and,

FIG. 9 is another perspective view thereof, shown in an alternative state of use.

The broken lines and the de-emphasized or half-toned portions shown within the FIGS. 8 and 9 represent environmental structure that form no part of the claimed design. The broken lines and the de-emphasized or half-toned portion shown with FIG. 6 represent portions of the health pot that forms no part of the claimed design.
